ELECTRIC DEFROSTER FOR REFRIGERATING COILS

Application filed December 15, 1927. Serial No. 240,258.

REISSUED

This invention relates to defrosting apparatus for refrigerating machines and more particularly to electrical means for this purpose.

5 A primary object of this invention is to provide means for automatically applying electric heat at predetermined intervals to the cooling units of a refrigerating plant whereby the accumulation of any appreciable amount 10 of frost on said units will be prevented.

Another object is to provide an intermittently operated device actuated by the refrigerating compressor for controlling the application of heat to the cooling units, and thereby 15 ensure the automatic defrosting of said units.

In carrying out these objects, the invention is susceptible of a wide range of modification without departing from the spirit or sacrificing any of the advantages of the claimed invention; there being shown in the drawings 20 for illustrative purposes a preferred and practical form, in which

Figure 1 represents a perspective of the electric heater control constituting a part of 25 this invention, parts being broken out and in section; and

Fig. 2 is a side elevation thereof.

In the embodiment illustrated the control device constituting a part of this invention 30 comprises an electric circuit closer 1 the wires 2 and 3 from which lead to heating coils 30, which are connected in series and arranged in contact with the cooling units 35 of a refrigerating plant, and which, when in operation melt off the frost and ice from the units. The contact 4 of this circuit closer is fixed while the contact 5 which cooperates therewith is 35 movable and is carried by a spring arm 6 mounted on a lever 7 fulcrumed at one end to a laterally extending bracket 8 carried by a suitable supporting structure. At the free end of the lever 7 is a roller 9 which is arranged in the path of the periphery of a rotatably mounted wheel 10 having a radially 40 extending cam 11 on the periphery thereof which is designed to engage the roller 9 during the rotation of the wheel and force the lever 7 toward contact 4 thereby causing the contact 5 carried by said lever to engage the 45 contact 4 and close the electric circuit, send-

ing current through the wires 2 and 3 to the heating coils above described.

The wheel 10 has an annular series of ratchet teeth 12 on one face thereof and is rotatably mounted on a suitable shaft 13. A 55 pawl 14 is positioned to engage the teeth and is carried at one end of an arm 15 pivotally mounted at 17 on a supporting structure 18. This arm 15 has depending therefrom a pointed prong 16 which is arranged in contact with sylphon bellows 19 which is controlled by a vacuum from the refrigerating compressor (not shown) with the pipe 20 leading to said compressor. This device is designed to be used in connection with what 60 is known as the flooded system which has a boiler in the refrigerator and is part of the coil and maintains a quantity of sulphur dioxide or other suitable refrigerant, the height of which is controlled by a 65 float valve, (not shown). It is understood that the function of the float valve in the header of the evaporator is to prevent the level of the liquid refrigerant from rising 70 above a certain height. When the pressure 75 within the evaporator, which is the suction pressure, falls below a minimum the bellows here shown at 19 which is connected by the pipe 20 with the evaporator, will have contracted sufficiently to open the motor switch 80 and also to pull down the lever 15 to the point where the pin 14 will engage behind another notch 12 of the wheel 10. The number of teeth 12 on the gear wheel 10 determine how long will be required before the circuit closes 85 on the heated coils. When the lever is down it will so remain until the bellows again expand which in turn causes the lever 15 to operate to turn the gear wheel another tooth. No defrosting, however, takes place until the 90 wheel 10 makes one complete revolution, being slowly turned by the actuation of one notch at a time. It will thus be seen that if the wheel 10 has 24 teeth it will defrost once in twenty-four hours for a few minutes and 95 then move away from the contact which closes the circuit for operating the electric heating coils. It will be understood that as the bellows 19 expands and contracts the lever 15 will be actuated and thereby rotate the wheel 100

10 by engagement of the pawl 14 with the teeth 12 of said wheel. It will thus be seen that the rotation of the wheel 10 of course causes the cam 11 to revolve and when said cam contacts the roller 9 it forces the lever 7 on which the roller is mounted away from the wheel, thereby causing the contact 5 of the circuit closer to engage the contact 4 and close the circuit and supply sufficient heat to the coils 30 to cause them to melt off the frost on the cooling units 35.

15 A coiled spring 21 is arranged between the lever 7 and an adjusting screw 22 mounted in the support S and is designed for controlling the engagement of the roller 9 with the periphery of the wheel 10, the wheel being made easier or harder to turn by adjusting the screw 22 for varying the tension of the spring 21 which opposes the bellows 19 to any desired 20 degree.

25 From the above, it will be obvious that this controlling device is automatic and through the circuit closer 1 the heat will be applied intermittently to the cooling units 35 for a short period of time, sufficient to melt the ice and frost which may accumulate thereon, in so many running hours of the machine.

30 From the above description, it will be obvious that after this device is once connected up with the refrigerating machine, no further attention is necessary, and it will automatically apply and cut-off heat at predetermined intervals controlled by the number of teeth 35 12 on the ratchet wheel.

35 Without further description it is thought that the features and advantages of the invention will be readily apparent to those skilled in the art, and it will of course be understood that changes in the form, proportion and minor details of construction may be resorted to, without departing from the spirit of the invention or its scope as claimed.

I claim:—

40 1. The combination with a refrigerating coil; of an electric heating coil arranged in close proximity thereto, and automatically operated means for energizing said heating coil at intervals whereby the refrigerating coil is freed from snow and ice.

45 2. The combination with a refrigerating coil; of an electric heating coil arranged adjacent thereto, and automatically operated means for energizing said heating coil at predetermined intervals whereby the refrigerating coil is freed from ice and snow.

50 3. The combination with a refrigerating machine including a coil and a compressor; of an electric heating coil arranged adjacent to said refrigerating coil, an electric circuit controlling said heating coil, and automatically operated means for opening and closing said circuit whereby the electric coil is energized at intervals and the ice and snow formed on the refrigerating coil melted thereby.

4. The combination of a sylphon bellows adapted to be actuated by a refrigerating compressor, normally open electric contacts, and means operated intermittently by said bellows for closing said contacts.

70 5. Means for closing an electric circuit comprising normally open electric contacts, a lever on which one of said contacts is mounted, a roller carried by said lever, a cam wheel mounted to engage said roller to operate said movable contact into engagement with the fixed contact at predetermined intervals, a pawl and ratchet mechanism for operating said wheel, and suitably operated bellows for actuating said ratchet mechanism.

75 6. The combination of a sylphon bellows adapted to be actuated by pressure in the suction side of a refrigerating clamp, a pawl carrying lever having engagement with said bellows and adapted to be operated thereby, a ratchet wheel having teeth located in the path of said pawl whereby the wheel is operated, a cam carried by the periphery of said wheel, normally open electric contacts, a lever on which one of said contacts is mounted 90 and having a roller positioned for engagement by said wheel cam for intermittently closing the contacts when said roller is so engaged.

80 7. The combination of a sylphon bellows 95 adapted to be actuated by pressure in the suction side of a refrigerating clamp, a pawl carrying lever having engagement with said bellows and adapted to be operated thereby, a ratchet wheel having teeth located in the path of said pawl whereby the wheel is operated, a cam carried by the periphery of said wheel, normally open electric contacts, a lever on which one of said contacts is mounted 100 and having a roller positioned for engagement by said wheel cam for intermittently closing the contacts when said roller is so engaged, and means for controlling the tension of the lever to vary the frictional engagement of the roller with the wheel.

105 Signed at Lexington in the county of Fayette and State of Kentucky this twelfth day of December A. D. one thousand nine hundred and twenty-seven.
